UNITED STATES PATENT OFFICE.

WILLIAM FRITZ, OF PHILADELPHIA, PENNSYLVANIA.

CANDY-COATING MACHINE.

1,090,608.

Specification of Letters Patent. Patented Mar. 17, 1914.

Application filed April 30, 1913. Serial No. 764,508.

To all whom it may concern:

Be it known that I, WILLIAM FRITZ, a citizen of the United States, residing in the city and county of Philadelphia, State of Pennsylvania, have invented a new and useful Candy-Coating Machine, of which the following is a specification.

My present invention relates to a candy coating machine which is especially adapted to be employed to coat blanks of material with chocolate, and consists of novel receiving mechanism, a novel construction of a conveyer for conveying the blanks between the coating mechanism, a novel discharging mechanism, novel means for securing strips of material to said discharging mechanism, and novel controlling means for such mechanism.

It further consists of a novel construction of a conveyer having coil spring cables and novel means for intermittently agitating and shaking the same and varying the amount of such agitation or shaking.

It further consists of a novel coating feeding mechanism whereby the coating material is first discharged against the upper and under side of the blanks to be coated, and afterward an additional supply of coating material is discharged against the upper ends of the blanks, novel means being provided for controlling the amount of chocolate passing through said feeding mechanism.

It further consists of a novel manner of mounting the discharge conduits for the coating material and novel means for reciprocating or oscillating the same, in order to decorate the blanks.

It further consists of novel means for causing predetermined spring cables to travel in a different plane from the other cables.

It further consists of a novel construction of a casing, whereby the coating material is maintained at a proper temperature, and a novel construction of a pumping mechanism for the coating material.

Other features of advantage and of construction will hereinafter more clearly appear in the detail description of my invention.

For the purpose of illustrating my invention, I have shown in the accompanying drawings a preferred form thereof which is at present preferred by me, since the same will give in practice satisfactory and reliable

results, although it is to be understood that the various instrumentalities of which my invention consists can be variously arranged and organized and that my invention is not limited to the precise arrangement and organization of these instrumentalities as herein shown and described.

Figure 1 represents a side elevation partly in section of a candy coating machine embodying my invention. Fig. 2 represents a side elevation of a portion thereof, showing certain parts of the driving mechanisms. Fig. 3 represents a plan view of my device. Fig. 4 represents a sectional elevation of a portion of Fig. 1, on line $x-x$ thereof. Fig. 5 represents, in perspective, a view of a portion of the discharging mechanism. Fig. 6 represents a perspective view of a portion of the discharge conveyer. Fig. 7 represents a section on line $y-y$ of Fig. 5. Fig. 8 represents a side elevation of a portion of my device. Fig. 9 represents a sectional view of a portion of the discharge conveyer, showing more clearly the manner in which strips of material are detachably connected therewith. Fig. 10 represents a plan view of the blank conveyer, certain parts thereof having been removed. Fig. 11 represents a plan view on an enlarged scale of a portion of a spring cable, seen in Figs. 1, 3, 10 and 12. Fig. 12 represents a side elevation partly broken away, showing more clearly certain details of construction.

Similar numerals of reference indicate corresponding parts in the figures.

Referring to the drawings:—The receiving mechanism comprises standards 1 in which are mounted journals 2, provided with adjusting devices 3 whereby the roller 4, mounted in said journals 2, may be laterally adjusted when desired.

5 designates the receiving conveyer which comprises an apron passing around the roller 4 and also around the roller 6 carried by a casing 7 supported in any desired manner. The roller 4 has the shaft thereof provided with a gear 8 which meshes with a gear 9, supported in any desired manner, and actuated by a connecting rod 10, provided with a pin 11 adapted to engage the walls of a slot 12 of a coupling 13, which latter is provided with a slot 14 in which is seated a pin 15, carried by a shaft 16.

17 designates a link adapted to give longitudinal movement to the coupling 13, said link being pivoted to a lever 18, which is

fulcrumed at 19 to the casing 7. It will thus be seen that the coupling 13 serves to interlock the shafts 16 and 10 upon the actuation of the lever 18.

- 5 The numeral 20 designates a link operatively connected with a coupling 21 keyed upon the shaft 16, whereby said coupling interlocks with the gear 22 loosely mounted on said shaft 16, and meshing with a gear 23. 10 16 This gear 23 is connected with a sprocket wheel 24 around which passes a sprocket chain 25, said sprocket chain also passing around the sprocket wheel 26 on the main driving shaft 27, said sprocket chain 25 also 15 passing around a sprocket wheel 28, carried by a clutch 29, as will be best understood by reference to Fig. 3. The clutch 29 is actuated by a crank 30' carried by a lever 30, in order to interlock with the driving roller 20 31, which is preferably grooved and rotatably carried by the casing 7, and adapted to drive a conveyer of a novel construction, which is preferably constructed of a series of cables 32, which, as best seen in Fig. 11, are 25 preferably constructed of coil springs united to form endless cables, any desired number of which may be employed. The lever 30 is pivoted by a separate bolt 31', also having pivotal connection with the link 20. It is 30 thus seen that when the outer end of the lever 30 is swung to the right, couplings 21 and 29 will be moved to their inner or active positions. The cables 32 receive the blanks discharged thereon from the conveyer 5 and 35 pass around upper rolls 33, which are preferably grooved and adjustably carried by the casing 7. The cables 32 also pass around a roller 34 carried by the casing 7. The rolls 33 are stationary and are carried by adjusting devices 35 which have in the present 40 instance threaded engagement with the casing 7, it being understood that the cables 32 travel in the grooves of the rolls 33. In order to cause blanks of large size to travel 45 in a straight line, I provide means for raising predetermined cables 32 to cause them to travel in a plane higher than the horizontal plane of the other cables, and in order to show one manner of accomplishing this 50 result I have shown rods 36 having adjustable thereon by means of set screws 37, pulleys 38. The shafts or rods 36 are mounted in journals 39, which are vertically adjusted by means of the set screw 40. 55 In order to provide means for vibrating the conveyer formed by the cables 32, in order to remove any excess of coating material from the blank, I provide a rod 41 passing beneath the upper stretch of the cables 32 and carried by brackets 42, which are mounted in the guides 43 so as to permit their vertical movement therein and are connected with levers 44, fulcrumed at 45 to the casing 7. One end of the levers 44 is 60 65 adapted to travel on the wipers or cams 46,

mounted on a shaft 47, which latter is provided with gears 48, meshing with gears 49 rotating in unison with the roller 34. In order to vary the amount of vibration or shaking imparted to the cables 32, I provide 70 adjusting screws 50, having threaded engagement with lugs 51 carried by the casing 7, said adjusting screws engaging the ends of the levers 44.

The casing 7 is provided with an inner 75 container 52, thereby forming a chamber 53 adapted to receive a heating or cooling medium which may be inserted therein through the port 54 and discharged therefrom through the controllable conduit 55. The driving shaft 27, which extends into the container 52, has mounted thereon a sleeve 56 provided with blades or paddles 57, which serve to stir and mix the coating material. This shaft 27 also has mounted thereon a 80 sprocket wheel 58, see Figs. 4 and 8, around which passes a sprocket chain 59, which latter also passes around a sprocket wheel 60, which is adapted to interlock with a clutch 61, controlled by a lever 62. The sprocket 85 wheel 60 is loosely mounted on a stud shaft 64 extending from the piston 63, while the clutch 61 is keyed to this stud shaft 64, which latter is seen in Fig. 4. The rotating piston 63 is slotted as at 65 to receive a piston blade 90 66 freely movable therein and adapted to engage the walls of the piston chamber 67, which communicates by means of a port 68 with the coating container 52.

69 designates a discharge port having a 100 controlling valve 70.

71 designates a discharge conduit communicating with the chamber 67 and with a laterally extending conduit 72, the contour of which will be best understood by reference to Fig. 4. This discharge conduit 72 is substantially U-shaped and provided with a slot 73 which extends around the conduit 72 on the under periphery of the upper portion thereof, and the upper periphery of the lower portion thereof, the end of said conduit 72 being provided with a valve sleeve 74 having a port 75 adapted to register with the port 76 in the conduit 72, when the sleeve 74 is rotated by means of the handle 105 77. The sleeve 74 is provided with a projection 78 which abuts against the conduit 71 and serves to align the ports 75 and 76. The conduit 72 is provided with a desired number of conduits 79 which communicate 110 by means of flexible connections 80 with conduits 81 having discharge ports at their end on the under side thereof as at 82, said ports being controlled by means of a sleeve 83 provided with adjusting means 84, such as for example a set screw. These conduits 81 are seated in slots 85 of a bar 86 mounted in journals 87, so as to reciprocate therein. 115 120 125

88 designates a spring interposed between a journal 87 and a washer 89 on the bar 86. 130

The bar 86 is provided with a roller 90 which coöperates with a cam 91, carried by a pinion 92, which meshes with a gear 93 on the shaft 16.

94 designates a clutch adapted to interlock with a pin 95 on the shaft 16 and with a pin 96 on a connecting rod 97, said clutch 94 being controlled by means of a lever 98. The connecting rod 97 is adapted to actuate a gear 99 meshing with a gear 100, which is operatively connected with a roller 101, mounted in journals 102, carried by standards 103, said journals 102 being laterally adjusted by means of the screws 104.

105 designates a discharge conveyer which passes around the roller 101 and around the roller 106 journaled in the casing 7. The conveyer 105 is provided with cross strips 107 having the front portion 108, upwardly deflected to form between such portion 108 and the conveyer 105 a space adapted to receive the end or tongue 109, of a strip 110, such as for example paper, on to which the coated blanks are discharged, it being understood from Fig. 5 that the adjacent strip 111 preferably laps over the strip 110 in order to prevent the coating material from touching the conveyer 105.

The operation of my novel coating machine is as follows: The articles to be coated are placed on the conveyer 5, it being understood that the lever 18 has been actuated to operatively connect the shafts 10 and 16 with the driving shaft 27, which latter is driven by any desired source of power the same being shown in the present instance as provided with pulleys 112. The articles or blanks pass from the conveyer 5 to the cables 32 which cause such blanks to travel between the U-shaped conduit 72, so that a stream of coating material, such as, for example, chocolate is presented to opposite sides of the blank. The amount of chocolate passing to the blanks may be controlled by actuating the handle 77, which permits the chocolate to return to the container 52 if desired, thereby varying the amount of chocolate passing to the slot 73. The cables 32 are intermittently vibrated or shaken, since the wiper 46 will raise one end of the levers 44, and as the ends of such levers 44 are released the cables 32 will be vibrated to remove the excess of coating material on the blanks to cause the excess to return to the container 52. By adjusting the set screws 50, the amount of vibration may be adjusted, as desired.

In some cases arising in practice it is advantageous to decorate the top of the blanks or to place an additional thickness of coating material thereon, in which case the conduits 81 are employed, although it is to be understood that the same are not essential in all cases and may be dispensed with. The conduits 81 may be wholly removed and

the branch conduits 79 plugged up or the sleeves 83 may be adjusted to close the ports 82 or to open the same to any desired extent. If the ports 82 are open as the blanks travel therebeneath they will receive an additional supply of coating material. If desired, this additional supply of coating may be discharged on to the blanks in an irregular manner due to the cam 91 reciprocating in the shaft 86 which carries the conduit 81. By removing the cam 91 this reciprocating feature of the shaft 86 may be dispensed with. The strips of paper or other material are secured to the discharge conveyer in such a manner that they may be readily detached after the coated blanks have been placed thereon.

It will be apparent that the receiving conveyer may be rendered inoperative by actuating the handle 18 and the discharge conveyer 105 may be rendered inoperative by actuating the lever 98. The pump is manually controlled by the lever 62 while the movement of the cables 32 is manually controlled by the lever 30.

Special attention is directed to the novel construction and manner of operation of the spring cables 32, and the novel manner of distributing the coating material with respect to the blanks to be coated.

It will now be apparent that I have devised a novel and useful construction of a candy coating machine, which embodies the features of advantage enumerated as desirable in the statement of the invention and the above description, and while I have, in the present instance, shown and described a preferred embodiment thereof which will give in practice satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a coating machine, a plurality of spaced laterally alined endless belts formed of coil springs, means to effect the longitudinal travel of the endless belts, means for retaining portions of certain of the endless belts in a different horizontal plane from corresponding portions of the other endless belts, and means to supply coating material to the articles carried by the endless belts.

2. A coating machine comprising a plurality of spaced laterally alined endless belts formed entirely of coil springs, means to vertically vibrate the endless belts, and means for supplying coating material to the articles upon the endless belts.

3. A coating machine comprising a plurality of spaced laterally alined endless belts formed of coil springs, means to effect

a longitudinal travel of the endless belts, pulleys engaging portions of certain of the endless belts, means to vertically adjust the pulleys, and means to supply a coating material to the articles upon the endless belts.

4. In a coating machine, a conveyer comprising laterally alined spring cables, means to impart a travel to said conveyer, a U-shaped discharge conduit between the arms 10 of which said conveyer travels and having a slot through its inner wall on both sides of said conveyer, and means to feed coating material to said discharge conduit.

5. In a coating machine, a conveyer comprising laterally alined spring cables, means to impart a travel to said conveyer, a U-shaped discharge conduit between the arms of which said conveyer travels and having a slot through its inner wall on both sides of 20 said conveyer, means to feed coating material to said discharge conduit, means to regulate the amount of coating material passing through said slot, devices to agitate said cables, and means to vary the amount 25 of agitation imparted to said cables.

6. In a coating machine, a conveyer comprising laterally alined spring cables, a bar passing beneath said cable, means to intermittently raise and lower said bar, coating 30 mechanism discharging coating material toward opposite sides of said conveyer, means to impart a travel to said conveyer, and devices for causing predetermined cables to travel in a different plane from that of 35 the other cables.

7. In a coating machine, a conveyer com-

prising laterally alined spaced cables, means to impart a travel thereto, a U-shaped discharge conduit having a slot through its inner wall, and a discharge port at one end, 40 a valve controlling said discharge port, and means to feed coating material to said U-shaped conduit.

8. A coating machine, comprising an endless belt conveyer provided with openings, 45 means to impart a longitudinal travel to the conveyer, a substantially U-shaped discharge conduit between which a portion of the conveyer travels, said substantially U-shaped conduit being provided upon its inner wall 50 on both sides of a portion of the conveyer with outlet means, means to supply coating material to said conduit, and means to apply a second coating to the previously coated material embodying conduits connected 55 with said substantially U-shaped discharge conduit.

9. In a coating machine, a conveyer for the articles to be coated, a U-shaped discharge conduit between which said conveyer 60 passes and having a slot extending longitudinally around its inner walls, and provided with a discharge port at one end, a valve to control said discharge port, and means to feed coating material at a predetermined temperature into said discharge conduit.
